Primary Examiner — S. Bryan Reinholdt, Jr.Assistant Examiner — Jillian Mazzola(74) Attorney, Agent, or Firm — Nixon Peabody LLP(57) CLAIM

The ornamental design for an apparel pattern, as shown and described.

DESCRIPTION

FIG. 1 is a view of a first embodiment of an apparel pattern on a bra.

FIG. 2 is a view of a second embodiment of the apparel pattern on a bra.

FIG. 3 is a view of the first embodiment of the apparel pattern shown in FIG. 1 on a bralette; and,

FIG. 4 is a view of the second embodiment of the apparel pattern shown in FIG. 2 on a tankini.

The evenly spaced broken lines (dash-dash lines) shown in FIGS. 1–4 depict environment and form no part of the claimed design. The dot-dot lines shown in FIGS. 1–4 depict portions of the apparel pattern that form part of the claimed design.

1 Claim, 4 Drawing Sheets(56)
